UNITED STATES PATENT OFFICE.

LOUIS HILL, OF AKRON, OHIO.

COMPENSATING GAS CUT-OFF.

Application filed February 14, 1925. Serial No. 9,186.

My invention relates to gas cutoff mechanisms of the type used in connection with gas stoves, for the purpose of enabling the flow of gas to be cut off automatically in 5 the event that the burner flame is extinguished under conditions where the gas would otherwise be left flowing but without burning.

More particularly stated I seek to produce 10 a compensating gas cutoff, so constructed and arranged as to reduce to a minimum the time required for the gas to be shut off, by action of the automatic mechanism employed for that purpose. In other words, I seek 15 to quicken the action of the automatic mechanism used for shutting off the gas supply.

Reference is made to the accompanying 20 drawings forming a part of this specification, and which like reference characters indicate like parts throughout the several figures.

Figure 1 is a fragmentary front elevation 25 showing one form of my improved compensating gas cutoff as used upon a gas stove.

Figure 2 is a fragmentary plan of the same.

Figure 3 is an elevation showing the mechanism of Figure 1, as this mechanism would be seen by an observer standing at the left 30 of this figure.

Figure 4 is a fragmentary front elevation of the mechanism as it appears with the stove heated and in action.

Figure 5 is a fragmentary front elevation 35 showing another form of my improved compensating gas cut off.

Figure 6 is a section on the line 6—6 of Figure 5 looking in the direction of the arrow.

Figure 7 is a section on the line 7—7 of Figure 5 looking in the direction indicated by the arrow.

I will first describe the mechanism in Figures 1 to 4 inclusive.

The stove body is shown fragmentarily at 45 5, and is provided with a sheet metal wall 6 extending vertically.

The burner tube is shown at 7 and the burner holes at 8. The burner tube is provided with a rose inlet head 9, and extending into this inlet head is a T head 10 for delivering gas into the burner tube.

A gas pipe is shown at 11, and is con-

nected with the T head 10 for the purpose of supplying gas to the burner tube. 55

Air is admitted through the rose head 9, along with the gas, in the usual manner.

The gas pipe 11 is provided with a hand valve 12, carrying a hand wheel 13 whereby this valve is actuated. 60

The gas pipe 11 is provided with another valve 14, controlled under certain conditions as hereinafter described by action of thermostatic mechanism for the purpose of shutting off the supply of gas to the burner. The 65 valve 14 is provided with a revoluble plug 15, this plug having mounted upon it two arms 16 and 17. The arm 16 serves as a handle for enabling the plug to be turned by hand, and the arm 17, though set by hand 70 as hereinafter described, is released by action of the thermostatic mechanism. The arm 17 is in its action something like a trigger, and I therefore designate it as the trigger arm. A tensile spring 18 is connected with 75 the valve plug 15 and with a fixed portion of the valve 14. The spring is always under tension, and its tendency is to turn the valve plug 15 in a counter-clockwise direction according to Figure 1. 80

The handle 16 and trigger arm, being fixed to the valve plug 15, always occupy the same position relatively to this plug.

With the handle 16 and trigger arm 17 extending upwardly, as indicated in full 85 lines in Figures 1, 2 and 3, the valve plug is in such position as to prevent the flow of gas through the valve 14. With the handle 16 and trigger arm 17 occupying the positions indicated for them by full lines in Figure 4, however, the valve plug 15 is in such condition that gas passes freely through it and into the burner. 90

The burner tube 7 is provided with a pair of lugs 20 integral with it, and extending through holes in these lugs is a shaft 21, carrying a rocking arm 22. The shaft 21 has the form indicated for it in Figure 2 and through the medium of this shaft the rocking arm 22 is journaled upon the lugs 20, and free to rock slightly, as indicated by full and broken lines in Figure 3. The rocking arm 22 is provided with a lug 22^a, integral with it and having the form indicated in Figure 3. This lug co-operates with the trigger arm 17, and holds the latter in the 100 105 trigger arm 17, and holds the latter in the

position indicated for it in Figure 4 while the stove is in action, as hereinafter described.

5 A spring 23 is connected with the rocking arm 22 and with the stove body. The tendency of this spring is to shift the arm 22 from the position indicated for it by full lines in Figure 3 to the position indicated for it by broken lines in that figure.

10 The arm 22 carries at its upper end a light thermostatic bar 24, so constructed and arranged that the upper end of this thermostatic bar is moved to the right according to Figure 4 when the bar is heated, so 15 that while the stove is in action, and therefore heated, the thermostatic bar 24 occupies the position indicated for it by full lines in Figure 4; and when the stove is not in action and is therefore cold, the thermostatic bar just mentioned occupies the position indicated for it by broken lines in this figure.

15 A heavy thermostatic bar appears at 25, and is supported upon a mounting 26. The 20 thermostatic bar 25 has the general form of an inverted L; or in other words, has its upper end bent to the left according to Figure 4. Because the thermostatic bar 28 is more massive than the thermostatic bar 24 25 it is relatively sluggish in its response to changes in temperature. The net result is that the thermostatic bar 24 moves more quickly in response to changes of temperature and has a wider range of movement 30 than the thermostatic bar 25.

25 The two thermostatic bars 24 and 25 are so proportioned, constructed and arranged that when the stove is idle and thus cold the bars occupy the respective positions indicated for them by broken lines in Figure 40, but when the stove is in action and thus heated the bars appear as indicated by full lines in this figure.

30 With the stove cold and the thermostatic bars 24 and 25 occupying the positions indicated for them by full lines in Figure 4, the thermostatic bar 24 is not in engagement with the thermostatic bar 25 and can therefore be moved freely past the same by rocking the arm 22. When, however, the bars are heated and occupy the positions indicated for them by full lines in Figure 4, the bar 24 is lodged against the adjacent portion of the bar 25, the rocking arm 22 45 being thereby locked and prevented from rocking under tension of the spring 23.

35 With the various movable parts occupying the relative positions indicated for them by full lines by Figure 3, the operator grasps the handle 16 and turns the same in a clockwise direction, so as to rock the plug 15 and bring the handle 16 and trigger arm 17 into the positions indicated for them by full lines in Figure 4. The downward movement of the trigger arm 17 causes this arm

to engage and pass by the center of the lug 22^a, carried by the rocking arm 22. Thus virtually this lug acts as a cam for actuating the arm 22 and parts carried by it, in order to allow the arm 17 to pass. As soon 70 as the arm 17 is below the center of the lug 22^a, however, the rocking arm 22 may resume the position indicated for it by full lines in Figure 4. With the movable parts in the position thus contemplated, the lug 22^a will now hold down the arm 17, and thus prevent the valve plug 15 from turning in response to the tension of the spring 18, provided the thermostatic bars 24 and 25 are heated by the stove; or in other words 80 provided the thermostatic bars 24 and 25 occupy the positions indicated for them by full lines in Figure 4. This leaves the rocking arm 22 locked in position, and it so remains while the stove remains heated. If 85 for any reason, however, the thermostatic bars 24 and 25 cool off, as for instance if the gas flame be extinguished by a sudden gust of wind, the thermostatic bar 24 shifts its upper end and is thus released from its 90 engagement with the thermostatic bar 25, and now rocks slightly in a counter-clockwise direction according to Figure 3, so as to allow the trigger arm 17, under tension of the spring 18, to pass upwardly and glide 95 over the adjacent curved surface of the cam 22^a. The tension of the spring 18 thereupon causes the valve plug 15 to turn, and cut off the supply of gas.

95 The operation of the form of my device 100 appearing in Figures 1 to 4 inclusive may be readily understood from the foregoing description.

With the stove cold the parts normally occupy the positions indicated for them in 105 Figures 1 and 2. Suppose that with the parts in these positions the stove is to be lighted.

The operator grasps the hand wheel 13, and by turning it opens the valve 12. The 110 gas passes up the gas pipe and through the valve 14, now open, and through the T head 10 into the burner tube 7, so as to escape from the openings 8. The operator by applying a lighted match to the gas escaping from these openings lights the stove. The heat of the stove causes both of the thermostatic bars 24 and 25 to bend, but the bar 24 bends more rapidly and swings to a greater distance than the bar 25, so that the 115 upper end of the bar 24 very soon overlaps the adjacent protruding end of the bar 25. This done, the operator releases the handle 16. The tension of the spring 18 is now 120 unable to turn the valve plug 15, because the trigger arm 17 is in engagement with the lug 22^a, and as the rocking arm 22 is unable to move because of the engagement of the thermostatic bar 24 against the thermostatic bar 25, the plug 15 remains in such position 125 130.

that the valve 14 is open. The handle 16 being released, the movable parts remain in the position they now occupy, and this continues as long as the gas flame continues to burn.

Suppose, next, that in consequence of a sudden gust of wind or the like the gas flame is blown out and the stove cooled off. The thermostatic bar 24 quickly straightens out, and the thermostatic bar 25 makes a movement toward resuming its normal position, thus traveling in the same direction as the portion of the thermostatic bar 24 with which it is in engagement. However, the thermostatic bar 24 travels more rapidly than the bar 25 and quickly outstrips the latter, so that the bar 24 is released from its engagement with the bar 25. This enables the rocking arm 22, now under control of the lug 22^a acting as a cam, to rock slightly against the tension of the spring 23, and by so doing to release the trigger arm 17. This allows the various movable parts to resume the positions normal to them when the stove is cold. The movement above described for the valve plug 15 causes the valve 14 to close and shut off the supply of gas.

It will be noted that the thermostatic bars 24 and 25 when actuated by changes of temperature, always move in the same direction, but at unequal speeds, the travel of the bar 24 being always greater than that of the bar 25. By this arrangement the bar 24 is allowed considerable play and the travel of the bar 25 reduces the distance otherwise necessary to be traveled by the bar 24 in order to enable it to control the gas supply as above described. This reduction in the distance traveled by the bar 24 is an important point, as it enables the automatic action of the valve 14 to be quickened considerably, and this is in the line of safety. Moreover by having both of the thermostatic bars 24 and 25 curved considerably to the right according to Figure 4 in consequence of the heat of the stove, and by giving the bar 24 a relatively wide range of movement accordingly, the chances for failure of the bar 24 to disengage itself from the bar 25 at the proper time are greatly diminished.

I will now describe the form of my device shown in Figures 5, 6 and 7.

Instead of the rocking arm 22 above described, I use a rocking arm 27 which carries at its upper end a thermostatic bar 28. The rocking arm 27 as a whole is mounted upon a shaft 29 which extends through lugs 20, as above described with reference to the shaft 21 shown in Figures 1 to 4 inclusive.

Near the lower edge of the sheet metal wall 6 and supported upon the wall is a plate 30, which acts as a limiting stop for the arm 17 when the latter is turned, as may be understood from Figure 5.

Connected with the T head is a pipe 31

and extending through this pipe is a copper wire 32 which does not quite fill it, and thus leaves a little room for the gas to pass upwardly through the pipe 31. These parts are so proportioned and arranged that when the stove is not in action, and consequently is cold, there is more room between the pipe 31 and the wire 32 within than when the stove is in action and consequently is heated. The idea is that the expansion of the copper wire 32 restricts the opening of annular form between the wire 32 and the pipe 31, and in doing this limits the carrying capacity of the pipe 31.

Located upon the wall 6 and adjacent the thermostatic bar 28 is a block 36, carrying a short and thick thermostatic bar 37 having the form indicated in Figures 5 and 6. The thermostatic bar 37 has substantially the form of an inverted L and is provided with a notch 38 and with a sloping edge 39 as indicated more particularly in 37.

The purpose of the sloping edge is to enable the thermostatic bar 28 to engage rather firmly the thermostatic bar 37, and to prevent the thermostatic bar 28 from moving too freely from the left according to Figures 5 and 6, while the two thermostatic bars 28 and 37 are in engagement.

The rocking arm 27 is provided adjacent its lower end with a lug 27^a of the form indicated in Figure 7. This lug holds the arm 17 down, when this arm is brought into the position indicated for it in Figures 5 and 7. That is to say the tension of the spring 18 tends to cause the arm 17 to swing upwardly, but this upward swing is for the time being retarded by the lug 27^a as may be understood from Figure 7.

The operation of the form of my device appearing in Figures 5, 6 and 7 may be readily understood from the foregoing description.

The gas being turned on, the pilot flames 34 and 35 are lighted.

The operator grasping the arm 16 turns it clockwise until it becomes horizontal as indicated in Figure 5. In doing this the rocking arm 27 swings slightly so as to enable the arm 27 to pass below the lug 27^a as indicated in Figure 7. The operator holds the arm 16 in horizontal position until after the gas is lighted and burning freely, so that the thermostatic bar 28 becomes heated and its upper end bends to the right. This brings the thermostatic bar 28 into engagement with the thermostatic bar 37. The rocking arm 37 is now unable to rock, because held from so doing by the thermostatic bar 37. The parts remain in the positions they now occupy so long as the stove continues to burn.

Suppose, next, that by a sudden gust of wind the flames of the stove are extinguished, so that gas continues to flow. When this

happens the cooling of the thermostatic bar 28 tends to cause this bar to straighten out, and in so doing, to disengage itself from the thermostatic bar 37. However, the sloping 5 of 39 slightly retards its movements and keeps the thermostatic bar 38 in rather close engagement with the thermostatic bar 37 for a moment. However, the thermostatic bar 28 is quickly released from the sloping 10 edge and swings to the left or in a counter-clockwise direction according to Figure 5. As soon as the thermostatic bar 28 is thus released, the rocking arm 27 is thereby rendered free to rock. Hence the upward 15 pressure of the arm 17, under tension of the spring 18, causes the arm 17 to rise and by acting upon the lug 27^a to rock the arm 27 back and forth within narrow limits. This movement of the rocking arm 27 is for the 20 purpose of releasing the arm 16, and this arm being released the tension of the spring 18 closes the valve through which gas is supplied to the T head and thence to the stove.

25 Except as otherwise above described, the structure and action of the mechanism shown in Figures 5, 6 and 7 is similar to that of the construction appearing in the other figures. Having thus described my invention what 30 I claim as new and desire to secure by Letters Patent is as follows:

1. In a gas stove the combination of a gas burner, a gas pipe leading to said burner, a valve connected with said pipe for controlling the flow of gas through said pipe to 35 said burner, a pair of thermostatic bars controllable by heat of the stove, one of said bars being more quickly responsive than the other to changes of temperature, said thermostatic bars being so positioned that they move into engagement with each other when subjected to uniformly high temperature, and move out of engagement with each other when the temperature of both bars is reduced, and mechanism connected with said 40 valve and with one of said bars, and controllable by one of said bars after its disengagement from the other bar, for the purpose of closing said valve.

50 2. In a gas stove the combination of a gas burner, a gas pipe leading to said burner, a valve connected with said pipe for controlling the flow of gas through said pipe to 55 said burner, a trigger arm connected with said valve for opening said valve, a rocking arm provided with a portion for engaging said trigger arm in order to restrain said trigger arm and thus prevent said valve from closing, means for closing said valve whenever said trigger arm is released, a 60 thermostatic bar carried by said rocking arm and movable therewith, and a thermostatic bar disposed adjacent said first mentioned thermostatic bar and fixed in position, said 65 second mentioned thermostatic bar being

relatively sluggish in its action as compared with said first mentioned thermostatic bar, and so positioned that when both of said thermostatic bars are heated to a uniformly high temperature they may lock together, but when both of said thermostatic bars are cooled, said first mentioned thermostatic bar moves out of engagement with said second mentioned thermostatic bar and thus releases said trigger arm.

3. In a gas stove the combination of a gas burner, a gas pipe leading to said burner, a valve connected with said pipe for controlling the flow of gas from said pipe to 70 said burner, a trigger arm connected with said valve for opening said valve and temporarily keeping it open, a rocking arm disposed adjacent said trigger arm and provided with a portion for engaging said trigger arm in order to hold said trigger arm and thus prevent said valve from closing, a 75 thermostatic bar carried by said rocking arm, another thermostatic bar disposed adjacent the path of travel of said first mentioned thermostatic bar, the thermostatic bars being so formed and arranged that they may lock together when both are subjected to a uniformly high temperature, thus preventing said rocking arm from releasing said trigger arm, said thermostatic bars being 80 unequally sluggish in response to changes of temperature, and so arranged that they disconnect from each other when both arms are subjected to a drop in temperature.

4. In a gas stove the combination of a 85 thermostatic bar having a general fixed position but movable in response to changes in temperature, said thermostatic bar being massive in construction and sluggish in its 90 thermostatic action, another thermostatic bar movable bodily in relation to said first mentioned thermostatic bar and also movable in response to its own temperature, said second mentioned thermostatic bar being movable more quickly than said first mentioned thermostatic bar as regards changes 95 of temperature, means for heating both of said thermostatic bars, a gas supply, and mechanism releasably held by said thermostatic bars and controllable by a differential 100 action thereof for shutting off said gas supply.

5. In a gas stove the combination of a pair 105 of thermostatic members so positioned and arranged so as to be heated together by the general heat of the stove, one of said thermostatic members being more sluggish than the other in responding to changes in temperature, a gas pipe for supplying gas to the 110 stove, a valve carried by said gas pipe for controlling the flow of gas to the stove, and mechanism connected with said valve and controllable by differential movements of 115 said thermostatic members for actuating said valve.

6. In a gas stove the combination of a gas burner, a gas pipe leading to said burner, a valve connected with said gas pipe for controlling the flow of gas therethrough to said burner, a trigger arm connected to said valve for opening said valve and temporarily holding it open, a rocking arm provided with a portion for engaging said trigger arm in order to restrain said trigger arm and thus prevent said valve from closing, means for closing said valve whenever said trigger arm is released, and a second thermostatic bar disposed adjacent said first mentioned thermostatic bar and fixed in position.
- 10 7. In a gas stove the combination of a gas burner; a gas pipe leading to said gas burner, a valve connected with said gas pipe
- 5 for controlling the flow of gas through said gas pipe to said gas burner, a trigger arm connected with said valve for opening said valve, a rocking arm provided with a portion for engaging said trigger arm in order to restrain said trigger arm and thus prevent said valve from closing, means for closing said valve whenever said trigger arm is released, a thermostatic bar mounted upon said rocking arm, and thermostatic mechanism located adjacent said rocking arm and coacting with said thermostatic bar for re-releasing said rocking arm.
- 15 20 25 30

Signed at Akron, in the county of Summit and State of Ohio, this sixth day of February, 1925.

LOUIS HILL.
